UNITED STATES PATENT OFFICE.

FRED HIMMEL AND ISIDORE HIMMEL, OF NEW HAVEN, CONNECTICUT, ASSIGNEES TO
THE HIMMEL BROS. CO., OF NEW HAVEN, CONNECTICUT, A CORPORATION.

STORE-FRONT CONSTRUCTION.

Application filed January 24, 1927. Serial No. 162,967.

This invention relates to improvement in store-front construction, that is, metal strips between which a sheet of glass is mounted. The inner and outer strips are connected together by screws, and frequently these screws extend at a right angle to the plane of the glass and it sometimes happens that the glass comes in contact with the screws, so that a jar will tend to break the glass by pressing against the screws. The object of this invention is to provide guards through which the screws extend, so as to provide a bearing to prevent the glass from coming in contact with the screws; a further object of the invention is to provide stops on one member to provide a bearing for the lower edge of the other member, and the invention consists in the construction as hereinafter described and particularly recited in the claims.

In the accompanying drawings:

Fig. 1 is a front view of a store-front construction embodying our invention;

Fig. 2 is a sectional view on the line 2—2 of Fig. 1;

Fig. 3 is a sectional view on the line 3—3 of Fig. 1; and

Fig. 4 is a sectional view of a modified form of stop.

In carrying out our invention, we employ an inner member 5 formed from sheet-metal in any desired manner, and the vertical wall 6 is formed with elongated slots 7, in which are mounted elongated fenders 8. These fenders are formed from tubing or folded up from sheet-metal, and preferably provided, near their inner ends, with an annular shoulder 9 to bear against the outer face of the wall 6, while the inner end 10 of the fender is bent over the inner surface of the wall 6, so as to be firmly interlocked therewith. An outer strip 11 of desired form is connected with the casing 12 by screws 13 extending through the fenders 8. These fenders provide a bearing for the edge of the glass 14 and, consequently,

prevent the edge of the glass from coming in contact with the screws 13, so as to be chipped thereby. The inner member 5 has a bottom flange 15, and from this flange a series of tongues 16 are turned upwardly and outwardly, so that the outer edge of the upper end of the tongue is in line with the outer edge of the flange 15, and this tongue and edge of the flange form a bearing for the lower portion 17 of the outer strip 11.

Instead of forming the tongues from the flange 15, as shown in Fig. 3 of the drawings, the tongues 18 may be formed on the inner edge of the outer strip so as to bear against the outer end of the flange 15, as shown in Fig. 4 of the drawings.

In both instances, these tongues provide spacers to properly locate the outer strips.

The construction shown in Fig. 4 of the drawings is not claimed herein, but is made the subject of a separate application filed December 28, 1927, Serial No. 242,991.

It is obvious, without illustration, that if the fenders are not formed from tubing, the edges need not necessarily meet, as the only object of the fenders is to prevent the contact of the edge of the glass with the attaching screws.

We claim:

1. A store-front construction, comprising an inner and an outer strip flattened, tubular fenders mounted in the inner strip, and screws extending through the outer strip and through the said fenders.

2. A store-front construction, comprising inner and outer strips, the inner strip formed with an opening, tubular fenders mounted in said opening and projecting forward therefrom, and screws extending through the outer strip and through said fenders.

In testimony whereof, we have signed this specification.

FRED HIMMEL.
ISIDORE HIMMEL.
